Primary Examiner — Wan Laymon*Assistant Examiner* — Clint A Samuel(74) *Attorney, Agent, or Firm* — Conley Rose, P.C.; Grant Rodolph; Brooks W Taylor(57) **CLAIM**

The ornamental design for a luminaire output lens array, as shown and described.

DESCRIPTION

FIG. 1 is a perspective view of a luminaire output lens array in accordance with the new design;

FIG. 2 is a front view of a luminaire output lens array in accordance with the new design;

FIG. 3 is a side view of a luminaire output lens array in accordance with the new design; and,

FIG. 4 is a perspective view of a luminaire output lens array with a luminaire shown in broken lines which forms no part of the claimed design.

The broken lines shown in the drawings are only provided to illustrate the environment of the design, and form no part of the claimed design.

1 Claim, 4 Drawing Sheets(56)
